ROLLING WINDOW SCREEN

Harry Herman, Brooklyn, N. Y.

Application September 30, 1949, Serial No. 118,915

1 Claim. (Cl. 160—23)

1

This invention relates to window screens and more particularly to the type adapted to be wound on a spring-roller.

The principal object of the present invention is to provide a rolling window screen which is adaptable to any type window, such as sash, double-hung, casement, etc., either in its entire opening, or lower, or upper portion thereof; which can be released from the inside of a room for accessibility to the outside without any obstruction whatsoever.

Another object of the present invention is to provide a rolling window screen which when unrolled is completely sealed and affords the utmost in protection against insects and similar pests, regardless of size.

Another object of the present invention is to provide a dust-proof compartment for receiving a rolling window screen and having means internal thereof for rendering a spring-roller operable.

Another object of the present invention is to provide a rolling window screen adapted to be unrolled upon the raising of a lower sash to thereby screen the opening thus afforded, and to be rolled when said sash is lowered; or to be unrolled upon the lowering of an upper sash to thereby screen the opening thus afforded, and to be rolled when said sash is raised.

Another object of the present invention is to provide means by which a rolling window screen may be locked to and easily detached from a window sash or sill when so desired.

Another object of the present invention is to provide means for the uniform lifting and lowering of a rolling window screen to thereby assure an ease of operation and the proper rolling thereof.

Another object of the present invention is to provide bracketing means whereby the screen enclosing compartment may be easily affixed to a window frame.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a front elevational view illustrating the present device screening the entire opening of a window.

Fig. 2 is an isometric view illustrating the

2

screen enclosing compartment and the brackets for the mounting thereof.

Fig. 3 is a fragmentary isometric view of one end of the compartment and the screen roller.

Fig. 4 is a fragmentary isometric view of the other end of the compartment and screen roller.

Fig. 5 is a fragmentary view illustrating the screen locking and screen sealing means.

Fig. 6 is an isometric view illustrating the present device as adapted to screen the opening effected by the raising of a lower window sash.

Fig. 7 is an isometric view showing the present device adapted to screen the opening effected by the lowering of an upper window sash.

In Fig. 1 the frame 10, comprising a roof 11, left and right side upright members 12 and 13, respectively, and a sill 14, represents any window frame, be it that of a sash, casement, or any other type. The compartment 15 fits between the side members 12 and 13 and is bracketed thereto by left and right-hand brackets 16 and 17, respectively, which are seen better in Fig. 2. Said brackets 16 and 17 are provided with bent-over rear and bottom portions 18 and 19, respectively, and when properly mounted to their respective side members 12 and 13 are adapted to receive therebetween the compartment 15, the rear bent-over portions 18 limiting the rearward extent of movement of the compartment 15 and the said bottom bent-over portions 19 providing support to said compartment. As also seen in both Figs. 1 and 2, an angle strip 20 is centrally disposed on and fixedly secured, as by spot welding or similar means, to the front of the compartment 15, and is provided with a hole 21 for receiving a screw or nail in order that said compartment may be secured in a proper operating position between the said brackets 16 and 17.

Fig. 1 also illustrates the manner in which the rolled screen 25, which will be described in detail hereinafter, is completely hidden in the said compartment 15, band the sealing channels 26 and the locking means 27, both of which will also be described hereinafter.

The roller 24 having the screening material 25 rolled thereon and seen in Figs. 3 and 4 is similar to the well-known spring-rollers used in window shades, and it will be sufficient herein merely to indicate that one end is provided with a stationary pivot pin 28 while the spring mechanism end is provided with a revolvable flat pin 29. At the end of the compartment related to the pivot pin 28 and fixedly secured thereto, as by

welding or similar means, is a pivot bracket 30

adapted to receive said pivot pin 28 and thereby support one end of the roller 24. At the other end of said compartment 15 and secured thereto is a plate 31 having its ends folded upon itself to provide slots 32 and 33, which slots are adapted to receive a bracket slide 35 having suitably fixed thereto a restraining bracket 36 for cooperating with the aforementioned flat pin 29. The proper positioning of the roller 24 in the said compartment 15 is dependent upon the bracket-slide 35. When positioning said roller 24 the slide 35 is removed from the slots 32 and 33 and the pivot pin 28 is first positioned in the bracket 30, then the flat pin 29 is inserted in its related bracket 36. Subsequently, the bracket slide 35 is inserted in the slots 32 and 33, and the restraining action of the bracket 36 upon the flat pin 29 permits the effectiveness and the ordinary operation of the spring-roller 24. As equally well seen in the Figs. 2, 3 and 4, a cut-out slot 37 in the underside of the compartment 15 permits the passage therethrough of the screening material 25.

Now, in order that the screening 25 might be sealed to prevent the passage of insects or other like pests between the sides thereof and the upright side members 12 and 13 of the window frame 10, and in order that said screen may be raised and lowered easily and guided to roll properly, sealing channels 26 are provided and are screwed or nailed to said frame side members 12 and 13. Said sealing channels 26 may be of any required length and of any suitable material, and as best seen in Fig. 5 are preferably formed of flat sheet metal strips folded lengthwise upon themselves and each having its sides 38 and 39 bent over in the same direction to thus form a channel 40. The screening 25 has attached at the free end thereof a rigid cross member 41, the ends of which and the sides of the screening being adapted to fit slidably in the aforementioned channels 40 of the left and right-hand sealing channels 26.

As also well seen in Figs. 1 and 5, each of the hereinabove mentioned locking means 27 comprises an angle member 43, the upright leg thereof being secured as at 44 to the said screen cross member 41 and having provided in its horizontal leg a rectangular aperture 45; and a turn bolt 46 adapted to pass through the said aperture 45 when aligned therewith and not to be passable therethrough when turned through an angle of 90 degrees. In both Figs. 1 and 5 the turn bolts 46 are mounted on the window sill 14 and the screen 25 is lockable thereto when rolled down and the said turn bolts are passed through the said apertures 45 and turned 90 degrees. When it is desired that the screens be opened the turn bolts 46 are aligned with the apertures 45 and with the assistance of the spring-roller 24 the screen is rolled up.

The just described arrangement provides for the screening of an entire window. However, as shown in Fig. 6, the present invention is also applicable to the screening only of the opening effected by the raising of a lower sash 47 and may be arranged to cooperate with said lower sash and be unrolled by the same action with which the sash is raised. This modification provides for the compartment 15 being mounted between the lower ends of the side members 12 and 13 of the frame 10 in the brackets 16 and 17 and held in position by the angle strip 20 secured to the sill 14. Also, the sealing channels 26 are of only

half-lengths and the above described turn bolts 46 are mounted on the upper side of the lower cross member 48 of the said sash 47. With this arrangement it will be seen that, when the screen is locked to the sash 47 by means of the turn bolts 46 and the angles 43 and the window is closed the screen is completely rolled and hidden in the compartment 15, and when the sash is raised the screen is automatically unrolled accordingly. Thus, protection is provided at all times during the opening of the window.

A similar arrangement is shown in Fig. 7 whereby the opening afforded by the lowering of the upper sash 50 is screened and the screen is automatically unrolled through the sash lowering operation. Here, as in Fig. 1, the compartment 15 is mounted between the upright members 12 and 13 of the frame 10 in brackets 16 and 17 and held in position by the angle strip 20 secured to the frame roof 11. But, as in the last described modification, the sealing channels 26 herein employed are half-lengths. Now, differing from said last described modification, the said turn bolts 46 are herein mounted on the underside of the upper cross member 51 of the said upper sash 50. Therefore, when the locking means 27 are effective, it will be seen that the lowering of the upper sash 50 effects the unrolling of the screen 25 and affords the utmost protection against the entrance of insects, and that the raising of said upper sash 50 effects the rolling of said screen 25.

It will be noted that in all of the above described arrangements, the compartment 15 when in its operative position has its open side covered by either the frame roof 11 or window sill 14, thus having its inner elements protected at all times from dust or other foreign damaging matter.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

In a rolling screen having a spring-roller with screening material rolled thereon and a pivot pin at one end of the roller and a flat pin at the spring end of the roller, a compartment having one side open, a pivot bracket secured at one end of said compartment for receiving the pivot pin, a pair of slide receiving slots at the other end of said compartment, a bracket slidably fitted in said slots, and a restraining bracket secured to said bracket and the flat pin being insertable into said restraining bracket when said first bracket is removed from said slots.

60 HARRY HERMAN.
